UNITED STATES PATENT OFFICE.

JAMES L. DALTON, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,121,716.

Specification of Letters Patent. Patented Dec. 22, 1914.

Application filed May 27, 1909. Serial No. 498,768.

To all whom it may concern:

Be it known that I, JAMES L. DALTON, a citizen of the United States, residing at Poplar Bluff, Butler county, Missouri, have invented a certain new and useful Adding and Recording Machine, of which the following is a specification.

This invention relates to adding and recording machines, and more particularly to machines of cross-carriage type such for instance as that shown in an application of Hubert Hopkins filed January 24th, 1903, Serial No. 140,390, eventuating in Patent No. 1039130, dated September 24, 1912.

The object of this invention is to provide mechanism whereby two or more separate totals may be carried in the machine at the same time.

The total mechanisms whereby the separate totals are computed and carried cooperate with recording mechanism operable to record the items including in the totals and also operable to record the totals and to clear the total mechanisms, or permit the latter to retain the totals therein as sub-totals to be included in a final grand total.

Other objects and manifold advantages of the present invention will become apparent from the following specification, reference being made to the accompanying drawings in which:

Figure 1 is a side elevation of a machine embodying the present invention with a printing section and key-board in section and the type-carriers advanced to recording position. Fig. 2 is a diagram showing specimens of the different results attained by this invention. Fig. 3 is a sectional view of the rear portions of a machine of the cross-carriage type, embodying the present invention. Fig. 4 is a perspective view of the mechanism whereby the type-carrier stop plate is operated to release the type-carriers. Fig. 5 is a horizontal sectional view of the rear portions of the machine immediately above the cross-carriage, showing the type-carrier stop plate and the mechanism controlling the same. Fig. 6 is a side elevation of the cross-carriage illustrating the type-carrier stop plate and the releasing devices. Fig. 7 is a perspective view showing the arrangement of the rear end of the type-carrier stop plate. Fig. 8 illustrates the construction of the lower extension of the stop plate controlling devices. Fig. 9 illustrates the rela-

tive positions of the stop-plate and the controlling devices when the machine is idle. Fig. 10 shows the engagement of one of the controlling levers with the stop-plate when the latter is in its elevated position. Fig. 11 shows the engagement of the other controlling lever with the stop-plate when the latter is in its movable position in which a part of the type-carriers are released. Fig. 12 shows the depressed or lowermost position of the stop-plate in which all of the type-carriers are released. Fig. 13 illustrates the relative positions of the stop-plate and the engaging gear device constituting a part of the recording mechanism at the right relative to the operator through the operation of which one column of items may be recorded and a separate total thereof maintained. Fig. 14 shows the engagement between the gear device and the stop-plate at the left, relative to the operator whereby another column of items may be recorded and a separate total thereof maintained. Fig. 15 shows the lower position of the stop-plate, in which all of the type-carriers are free to move to perform their recording functions.

The machine as at present on the market includes a key-board on which the keys are arranged in convenient manner in transverse rows, the stems of the keys extending through slots in the key-board plate and being connected with, or forming part of the key levers 2, which project rearwardly and converge at their rear ends and are provided with vertical extensions 3 arranged in the same vertical plane. Two transverse rails 4 are supported near the rear end of the machine and the carriage 5 is provided with rollers 6 operating above said rails. A hook 7 attached to one side of the carriage engages under one of the rails and thereby prevents derailment of the carriage during operation and during movement and transportation of the machine. Within the carriage 5 the vertically movable pins 8 are arranged, said pins being in longitudinal rows, the pins of each row being in the same vertical plane and the row at the left relative to the operator when the machine is in idle position being above the row of extensions 3. When any key is operated one of the pins 8 in the first row will be moved upwardly and at the same time the carriage 5 will be moved one step toward the left

which is sufficient to position the second row of pins in said carriage above the termini 3. This leftward movement of the carriage is controlled through an escapement mechanism 9 of known construction, and a train of devices connecting said escapement with the carriage. Said devices include the escapement sector 10 attached to the vertical shaft 11, and the gear segment 12 on the upper end of said shaft 11 enmeshed with a rack 13 rigidly connected to one side of the carriage 5. The escapement 9 has a bar 14 extending over the key levers 2 whereby the escapement will be operated at each operation of a key. In this way by successive operations of the keys any number may be set up or registered in the carriage 5, the pins 8 being positioned to represent the digits of a number. After the number has thus been represented in the carriage, such number may be recorded and added.

The recording mechanism comprises a series of type-carriers 15 swinging from a shaft 16, said type-carriers being arcuate in form and extending forwardly. On the forward end of each type-carrier is a series of type 17, said type being movable with respect to the type-carriers. A platen 18 is attached on a shaft 19 mounted in a carriage 20 and is operable in connection with the feed rolls 21 to feed the paper across its front surface where records may be made by driving the type 17 against an interposed ink ribbon. Coöoperating with each type-carrier there is a member 22, said member swinging from the shaft 16 and provided on their lower ends with arcuate racks 23. Said members 22 have extensions connected by pin and slot connections 24 with the type-carriers 15 so that each type-carrier has independent movement equivalent to the length of its slot. The racks 23 are spaced apart the same distance as the space separating the rows of pins 8 in the carriage. Each rack 23 has a projecting heel 24 at its rear end which will engage against the pins 8 which are elevated at the time the racks and type-carriers are moved forwardly to record. A stop-plate 25 is pivoted to a support 26 in the carriage 5 leftward from the rows of pins 8. Said plate is split for a portion of its length as shown at 27. That portion of the plate at the right from the cut 27 is bent downwardly somewhat lower than the portion at the left. In idle position of the parts, the plate 25 is under the racks 23 and the rear edge of the plate is supported immediately in front of the heels 24 so that when type-carriers and racks are actuated forwardly, their forward movement will be stopped by the heels 24 coming into contact with the rear edge of the plate 25. In the present instance, the arrangement is such that the four racks at the right 65 relative to the operator will engage with

the lower portion of the plate 25 while the five remaining racks will engage with the upper portion of the plate 25. When the carriage 5 is moved leftwardly as before described, the plate 25 is also transported leftwardly and at each step moves from in front of one of the heels 24 so that as many racks and type-carriers will be free to move forwardly as there were figures in the number set up in the carriage. After the number has been thus set up in the carriage and the type-carriers have advanced to their forward positions and been properly positioned by engagement of the heels 24 with the pins 8, the number represented by the type 17 at the printing line will be automatically recorded by a set of hammers 28 striking the front ends of the type. Return movement of the type-carriers and racks is effected by a rod 29 supported in front of the vertical portions of the type-carriers and racks by arms 30 depending from the shaft 16, said rod being moved in any convenient manner. Total wheels 31 are arranged to become enmeshed with racks 23 on return movement of said racks thereby to add the items after they are recorded. After any series of items has been added, the total represented in the wheels 31 may be recorded and said wheels restored to clear position or the total may be retained in the wheels. The mechanism for accomplishing this result as embodied in the machines of the character referred to at present on the market, and as disclosed, for instance, in the British patent to Hopkins, No. 854, of 1904, includes a totals recording key 32 having a stem projecting through a slot in the key-board plate and pivoted at its lower end to the front end of a lever 33, the rear end of which extends under the horizontal arm of a bell-crank 34. A link 35 connects the bell-crank 34 with a lever 36 pivoted to a shaft 37 at the rear of the machine. Said lever 36 also projects above the shaft 37 and an arm 38 pivoted on the shaft 37 coöperates with the upper portion with the lever 36 to support a horizontal rod 39, which will be swung forwardly whenever the total key is depressed. A cam plate 40 is mounted in the carriage 5 and is provided with an oblique slot 41 in which a pin on an extension of the plate 25 projects. When the total key is depressed and the rod 39 is swung forwardly, said rod will engage against the rear end of the cam-plate 40 and push said plate forwardly thereby drawing downwardly the plate 25 until the lower portion of said plate at the right of the cut 27 is entirely below the heels 24 of the four racks at the right. This will permit said racks and the coöoperating type-carriers to move forwardly, the racks remaining enmeshed with the total wheels while the totals recording key is down and being

stopped thereby. In this way the total contained in the four wheels at the right relative to the operator, may be recorded and by holding the total key in its depressed position, said wheels may be cleared or, by releasing the total key, the total may be retained in the wheels.

The mechanism so far described is contained in the machine as at present on the market and the construction is well known with the single exception that the stop-plate 25 in the machine as now manufactured is not split as at 27 and when the totals recording key is depressed the plate 25 will be lowered to release all of the gear parts and type-carriers. As above described, the rod 39 when it engages against the end of the cam-plate 40 will release only that number of gear parts and type-carriers, which engage against the plate 25 at the right of the cut 27. The present invention includes mechanism operable to move the cam-plate 40 effectively to release the plate 25 from all of the gear parts 23. Said mechanism is arranged and operates as follows:

A bell-crank lever 42 is pivoted within the machine and has one arm projecting through a slot in the keyboard plate convenient for manual engagement. A link 43 is pivoted to the other arm of said lever 42 and the rear end of said link is pivoted to a bell-crank lever 44, pivoted, in this instance, to a bracket on one of the rails 4. A link 45 connects the opposite arm of the lever 44 with a sleeve 46 slidably mounted on the rod 39. Forward movement of the lever 42 will move the sleeve 46 from the position shown by dotted lines in Fig. 5 to a position rearward from the cam-plate 40, thereby interposing one side of said sleeve between the end of said cam-plate and said rod 39. From the foregoing, it is obvious when the totals recording key 32 is depressed, the sleeve 46 will engage against the end of the cam-plate 40 and push said cam-plate forwardly a greater distance than would the rod 39. This movement of the cam-plate 40 is sufficient to draw downwardly the plate 25 below the heels 24 on the racks 23. The leaf spring 47 attached to the bracket to which the lever 44 is pivoted has a projection 48 over which one arm of the lever will ride when oscillated and which will engage against one side or the other of said lever and hold the same in either one of its two adjustments. Slight pressure on the lever 42 is sufficient to move the lever 44 in either direction and the spring 47 and its projection 48 will be effective to hold the parts in the desired adjustment. When the sleeve 46 is positioned as shown in Fig. 5 operation of the total key will result in release of the plate 25 from all of the gear parts and thereby permit said gear parts and the type-carriers to be moved forwardly to record

the total represented in the total wheels leftward from the cut 27 as well as any total represented by all or any number of the total wheels. At one side of the type-carriers and gear parts a bracket 49 is supported and a bell-crank lever 50 is pivoted to said bracket, one arm of said lever being substantially vertical and the other arm being substantially horizontal. A second lever 51 is pivoted on the same stud with the lever 50 and has pin-and-slot connection 52 with said lever 50. The spring 53 connecting the levers 50 and 51 with the bracket 49 actuates the vertical arms of said levers forwardly toward the rear edge of the plate 25. The type-carrier at the left is provided with a projection 54 arranged, in idle position, to engage against the upper edge of the horizontal arm of the lever 50 and thereby hold the vertical arms of said lever 50 and the lever 51 out of engagement with the plate 25, leaving said plate free to be operated by movement of the cam-plate 35. When the rod 29 moves forwardly to permit printing by any of the type-carriers all of the type-carriers move forwardly until stopped by the pin-and-slot connection 24. This movement of the type-carrier having the projection 54 releases the lever 50 and the lower arm of said lever will be actuated forwardly. A notch 55 is formed near the lower end of the lever 50 and forward movement of said lever will cause the plate 25 to be engaged in said notch, which occurs every time an item is recorded and added by the machine. This is effective to prevent accidental displacement of the plate 25 during listing operations and insures accurate work by the machine.

When the sleeve 46 is held in-operative and the total key is depressed the plate 25, as above described, is also depressed to its middle position. When the type-carriers are then operated to record the total represented in the total wheels at the right, the levers 50 and 51 will again be actuated forwardly. In this operation the rear edge of the plate 25 is below the notch 50 and will be engaged by a notch 56 in the lever 51 thereby being held against accidental displacement and insuring accuracy in operation of recording the total. When the plate 25 is depressed to its lowermost position the rear edge thereby is below the end of the lever 50 but is engaged by the lever 51 as shown in Fig. 12. This prevents accidental displacement of the plate 25 while the total represented in the wheels at the left is being recorded. The pin-and-slot connection stops the lever 50 when the lower end thereof assumes the position as shown in Fig. 12. By mechanism of this character various kinds of work may be performed on the machine. For instance, parallel columns of items may be recorded simultaneously as

shown at the top of Fig. 2 and separate totals thereby may be carried in the machine at the same time and then recorded simultaneously. Again, one column of 5 items may be recorded by the type-carriers at the right relative to the operator as shown at A in Fig. 2 and the total of such column recorded as shown at B. Then this total may be introduced in the machine 10 through the keys 1 and the carriage 5 and recorded as an item or sub-total in a column at the left of the column A as shown at C. Then other items may be recorded in the column A a total thereof recorded in the 15 same column and this total again introduced into the machine and recorded in the column C, as item or sub-total, after which the total of the numbers recorded in the left hand column may be recorded as shown at 20 D. A third specimen of the work of which this machine is capable of performing is shown at the bottom of Fig. 2 in which two columns of items are recorded simultaneously and the totals thereof recorded at 25 E and F, respectively and the machine cleared. After the totals have been thus ascertained they may be again introduced into the machine and recorded in one column or other as shown at G making a grand 30 total H. The machine may also be used to perform work of various other kinds, but the specimens illustrated are sufficient to enable those skilled in this art to comprehend the nature and the purpose of the 35 invention. It will be understood, of course, that the machine performing this work, may be split so that the ciphers at the right of the numbers in the left hand column or columns will not be recorded, thereby enabling the operator to list a single column 40 of numbers on the left or parallel columns printed simultaneously, specimens of both of which are shown in Fig. 2.

I am aware that there may be variations 45 in the constructions, combination and arrangement of this invention without the least departure from the spirit and scope of the invention. Also that the machine may be used to perform various classes of work 50 other than those illustrated and I do not restrict myself to specific constructions or arrangement nor to specific functions, but what I claim and desire to secure by Letters Patent is:

55 1. The combination with adding mechanism, and recording mechanism whereby said adding mechanism may be operated to add in separate parts thereof a plurality of numbers simultaneously recorded by said 60 recording mechanism, said recording mechanism being operable effectively to record any total or totals represented in said adding mechanism, of means for holding one part of the aforesaid adding mechanism in stationary position with a total represented 65

therein while a separate total in another part of the same adding mechanism is being recorded.

2. The combination with a single group of adding wheels, an equal number of racks 70 operable to mesh with and operate all of said adding wheels at one time to produce a single total in all of said wheels, and means for operating said racks to introduce separate totals in said single group of wheels, of mechanism 75 operable in connection with said racks to record one total represented in said group of wheels and return to idle position the wheels in which said recorded total was contained while the wheels containing another total 80 and the actuating racks therefor remain stationary.

3. In an adding machine, a platen arranged to hold paper, a carriage, means operable to set up two separated numbers in 85 said carriage, mechanism operable to record said two numbers at one operation after they have been set up in said carriage, a single group of adding wheels, means for operating said adding wheels to add a plurality 90 of separate numbers at the same time, and means for operating said recording mechanism and certain of said adding wheels to clear the total from the adding wheels which are so operated and at the same 95 time preventing clearing of the remaining adding wheels, substantially as described.

4. In an adding machine, a platen arranged to hold paper, a carriage means operable to set up numbers in said carriage, a single group of adding wheels, mechanism 100 operable to introduce one or more numbers from said carriage into said adding wheels at a single operation, and means for recording on said platen and clearing from said adding wheels one of said numbers and at the same time retaining certain of said adding wheels in position to represent the other of said numbers, substantially as described. 110

5. In an adding machine a platen arranged to hold paper, a carriage, means operable to set up numbers in said carriage, a single group of total wheels, mechanism for 115 causing said total wheels to represent a plurality of totals at the same time, and mechanism operable to record one of said totals and at the same time restore to idle position the wheels wherein said total was represented while holding another total in others of said wheels, substantially as described. 120

6. The combination with a single group 125 of adding wheels, a rack arranged to mesh with each adding wheel, mechanism for operating all of said wheels at one time to produce a single total, and means for causing said racks to operate said wheels to produce and retain separate totals at the same time, 130

of mechanism operable to record both of said separate totals at the same time, or only one of said totals, as desired, substantially as described.

- 5 7. In an adding machine, the combination with adding mechanism operable to produce, and retain at the same time, a plurality of totals, and a carriage whose operation is necessary before said adding mechanism 10 may be operated, of recording mechanism, a total recording key, and means whereby said recording mechanism will record one or more of said totals, as desired, after said totals recording key is operated, substantially as 15 described.

8. In an adding machine, the combination with a group of adding wheels, and a carriage whose operation is necessary before said wheels may be operated, of mechanism 20 for operating any number of said adding wheels to represent a total, or to represent two separate totals at the same time, as desired, and clearing mechanism manipulative to clear from said adding wheels one of the 25 totals represented therein, and at the same time to retain in certain of said adding wheels the other total represented therein, substantially as described.

9. In an adding machine, the combination 30 with a movable carriage, mechanism operable to set up numbers in said carriage, mechanism operable to record the numbers set up in said carriage, of a laterally immovable group of adding wheels, means for operating said recording mechanism effectively to record a plurality of parallel columns of 35 items and at the same time operating said adding wheels effectively to add and retain separate totals of said separate columns, and 40 clearing mechanism manipulative to clear one or all of said totals from said adding wheels as desired, substantially as described.

10. In an adding machine, the combination 45 with a shaft, a series of racks pivoted on said shaft, a carriage whose operation is necessary before said racks may be operated in adding operations, means for operating said carriage, a second shaft and a group of adding wheels on said second shaft, of mechanism 50 for operating said racks in adding operations to actuate said adding wheels to represent two separate totals at the same time, and mechanism for recording one of said separate totals alone or both of said totals at 55 the same operation, as desired.

11. In an adding machine, the combination 60 with a movable carriage, keys for setting up numbers in said carriage, and recording mechanism operable to record two separate numbers at a single operation, of a group of adding wheels, devices for causing said adding wheels to add and retain separate totals when separate numbers are recorded as aforesaid, and clearing mechanism

manipulative at the will of the operator to 65 clear one or more of said totals at one operation, as desired, substantially as specified.

12. In an adding machine, the combination of a shaft, a group of adding wheels mounted for independent rotation on said 70 shaft, racks for actuating said adding wheels, a support for said shaft, automatically operable connections for moving said shaft effectively to entrain said adding wheels with said racks, a carriage whose operation is necessary before said racks may be operated, mechanism for operating said racks to set said wheels to represent two separate totals at the same time, and mechanism operable to record one of said totals 80 alone or both of said totals at the same time, as desired, substantially as specified.

13. In an adding machine, the combination with a group of adding wheels, a series of racks for operating said adding wheels, 85 type moved with said racks, and hammers for driving said type to record, of a carriage whose operation is necessary before said racks may be operated, keys operable to set up one or more numbers in said carriage, 90 means for actuating said racks and said adding wheels to add said numbers to produce separate totals in said adding wheels, and mechanism for operating said racks and said adding wheels and said type to record 95 one of said totals alone or both of said totals at a single operation, as desired, substantially as specified.

14. In an adding machine, the combination with a movable carriage, and mechanism operable to set up numbers in said carriage, of racks limited in their movements by said carriage, type, hammers, a platen arranged to feed paper to said type, mechanism for operating said racks and 105 type and hammers effectively to record at a single operation any two numbers set up and retained in said carriage, means for retaining separate totals of numbers recorded, and means for recording one total while retaining the other. 110

15. In an adding machine, the combination with a shaft, a series of adding wheels mounted for independent rotation on said shaft, racks movable effectively to operate 115 said wheels, a support for moving said shaft to entrain said adding wheels with said racks, and a carriage whose operation is necessary before said racks may be operated, of mechanism for operating selected ones of said racks to clear a part of said adding wheels while the remainder of said racks remain stationary with a total contained in the remaining adding wheels. 120

16. In an adding machine, the combination with a group of adding wheels, a series of racks for operating said adding wheels, type controlled by said racks and hammers 125

- for driving said type to record, of a carriage whose operation is necessary before said racks may be operated, keys operable to set up one or more numbers in said carriage 5 mechanism for operating said racks and type and hammers to record one or more numbers at a single operation, means for causing said racks to operate said adding wheels to add the numbers recorded and retain separate totals thereof, and mechanism whereby one of said totals may be recorded while the other remains unrecorded, substantially as specified.
17. In an adding machine, the combination with adding mechanism, racks for operating said adding mechanism, and means for operating said racks and adding wheels to add in separate groups of said adding wheels, a plurality of numbers effectively 10 to retain separate totals of said numbers so added, a stop plate for holding said racks, means for moving said stop plate to different positions to release any desired number of said racks and to hold any desired number 15 of said racks, and means for operating said racks and a corresponding group of said adding mechanism after said stop plate has been so positioned, substantially as 20 specified.
18. In an adding machine, the combination with adding wheels, and racks for actuating said adding wheels, of an abutment for preventing operation of said racks, means for positioning and holding said 25 abutment in position to enable certain of said racks to operate and to prevent others of said racks from operating, and means for operating the racks released by said abutment.
19. In an adding machine, adding wheels, racks for actuating said adding wheels, an abutment for preventing operation of said racks, means for moving said abutment to enable said racks to operate in adding operations, and means for moving said abutment to enable certain of said racks to operate in clearing operations and at the same time to prevent operation of others of said 40 racks.
20. In an adding machine, adding wheels, racks for actuating said adding wheels, a carriage controlling the operation of said racks, means controlled by said carriage for preventing operation of said racks, mechanism controlling said means to enable said racks to operate in adding operations, independent devices controlling said means to enable certain of said racks to operate in clearing operations and to prevent others of said racks from operating in clearing operations, and means for operating said racks.
21. In an adding machine, the combination with a series of racks operable in adding and clearing operations, of an abutment 45
- manipulative to enable varied numbers of 65 said racks to be operated in clearing operations.
22. In an adding machine, the combination with racks operable in adding and clearing operations, and a carriage for controlling said racks in adding operations, of a device whose operation is necessary before 70 said racks may be operated in clearing operations, and means for operating said device to enable varied numbers of said racks 75 to be operated.
23. In an adding machine, the combination with adding wheels and racks operable in adding and clearing operations, of manipulative means operative at the will of 80 the operator irrespective of the number of digits represented in the adding wheels for determining the number of said racks which may be operated in clearing operations.
24. In an adding machine, the combination with adding wheels, and racks for operating said adding wheels in adding and clearing operations, of a device under control of the operator for determining the 85 number of said racks and wheels which may 90 be operated in clearing operations.
25. In an adding machine, the combination with adding wheels arranged in numerical orders, racks arranged in numerical orders and operable in cooperation 95 with said adding wheels in adding and clearing operations, and means coöperating with said adding wheels to determine which of said racks may operate in clearing operations, of means under control of the operator for 100 varying the number of said racks which may be operated in clearing operations, said last-named means being manipulative by the operator to vary the number of racks which may operate, irrespective of the number of 105 digits represented in said adding wheels.
26. In an adding machine, the combination with adding wheels and racks operable in adding and clearing operations, of a carriage for controlling said racks in adding 110 operations, a stop device in said carriage for the racks which are not to be operated in adding operations, and means for disengaging said stop device from varied numbers of said racks independently of any operation of said carriage.
27. In an adding machine, the combination with racks operable in adding and clearing operations, of a device for determining the number of said racks which may 120 be operated in clearing operations, and means for latching said device in different positions.
28. In an adding machine, the combination with adding wheels, and racks for operating said adding wheels in adding and clearing operation, of a device for holding 125 said racks, means for operating said device

to release varied numbers of said racks in clearing operations, and means for latching said device in its different positions.

30. In an adding machine, the combination with racks operable in adding and clearing operations, of a device for holding the racks in their idle positions, and means for operating said device to release varying numbers of said racks in clearing operations.

31. In an adding machine, the combination with racks operable in adding and clearing operations, of a device for holding said racks in their idle positions, means for moving said device in one direction varying distances to release varying numbers of said racks in adding operations, and means for moving said device in another direction varying distances to release varying numbers of said racks in clearing operations.

32. In an adding machine, the combination with racks operable in adding and clearing operations, of a device for determining the number of said racks which may be operated in adding and clearing operations, means for moving said device to enable varying numbers of said racks to be

operated in clearing operations, and means for latching said device in different positions.

33. In an adding machine, the combination with racks operable in adding and clearing operations, of a device for holding said racks in their idle positions, and means for moving said device to release varying numbers of said racks in clearing operations.

34. In an adding machine, the combination with racks operable in adding and clearing operations, of a pivoted element for holding said racks in their idle positions, means for moving said element varying distances to release varying numbers of said racks in clearing operations, and means for latching said element in its different positions.

In testimony whereof I have hereunto set my hand in the presence of two witnesses this 1st day of May, 1909.

JAMES L. DALTON.
